WILLIAM N. STEVENSON, OF ATTLEBORO, MASSACHUSETTS, ASSIGNOR TO AMERICAN REINFORCED PAPER COMPANY, OF ATTLEBORO, MASSACHUSETTS, A CORPORATION OF MASSACHUSETTS

METHOD FOR MAKING COMPOSITE WATERPROOF SHEET MATERIAL

Application filed January 29, 1932. Serial No. 589,657.

This invention relates to a method for producing a composite waterproof material having a sheet of textile fabric at one or both faces, and more particularly to a method for preventing a heated waterproof adhesive applied to one face of the textile fabric from penetrating through to the opposite face of the fabric.

Multiply waterproof material formed of two sheets of paper secured together with a waterproof adhesive has been made heretofore and is extensively used both with and without reenforcing elements secured between the sheets of paper, and recent efforts have been made to provide a multiply waterproof material having a sheet of textile fabric at one or both faces of the composite sheet, but difficulty has been experienced in preventing the waterproof adhesive applied between the sheets from penetrating through the textile fabric to the outer face thereof.

It is found in practice that if a woven fabric has a coating of hot waterproof adhesive, such for instance as hot asphaltum, applied to one face of the fabric, it penetrates through to the opposite face. This is objectionable in many cases as the adhesive at the outer face of the fabric may discolor the fabric or make it tacky, and may be otherwise undesirable.

The present invention, therefore, relates to composite waterproof sheet material formed of a plurality of sheets, at least one of which is a textile fabric secured to the other sheet or sheets by a waterproof adhesive, and the invention more particularly resides in the method for preventing the heated waterproof adhesive provided between the sheets from passing through the apertures of the textile fabric to the outer or exposed face thereof.

This is accomplished in accordance with the present invention by chilling the textile fabric, either before or immediately after the hot adhesive is applied, so that the chilled fabric will cause the contacting surface of the heated adhesive to set or congeal and thus prevent penetration through the fabric to the opposite surface.

It is contemplated that the sheets to be

united to form the composite or multiply fabric will be advanced towards the uniting point at high speed, and if the fabric is to be chilled while it is being fed along its path of travel, it is important to provide a chilling device of appropriate surface area to thoroughly chill the rapidly traveling fabric.

While different means may be employed to cool the fabric, this is accomplished in the construction shown by passing the fabric along a relatively larger metal plate which is chilled by any suitable means, such as, by spraying cool water upon the opposite face.

The strength of the multiply fabric may be increased as desired by introducing reenforcing material between the outer sheets and adhesively securing the reenforcing material therebetween.

The various features of the invention will be further understood from the following description when read in connection with the accompanying drawings showing different constructions for carrying out the present method.

In the drawings:—

Fig. 1 is a perspective view of one form of mechanism for carrying out the method of the present invention;

Fig. 2 is a perspective view of a modification; and

Fig. 3 is a diagrammatic view in vertical section of a third construction employing the present method.

In Fig. 1 of the drawings is shown mechanism for manufacturing composite waterproof sheet material comprising an upper sheet 10 and a lower sheet 11 having confined between them reenforcing fibres.

The upper sheet 10 which may be formed of woven cotton or other textile material is shown as supplied by the roll 14 supported on a floor 15 above the machine for drawing out the reenforcing fibres 12 and 13 and applying therebetween the sheets 10 and 11. The sheet 10 may be drawn over the guide rollers 16 and 17 and downwardly through a slot 18 in the floor 15.

The lower sheet 11 may be formed of paper or textile material and is supplied by the

- roll 19 supported above the floor 20. It is desirable to apply a coating of waterproof adhesive to the upper face of the sheet 11 and while various coating devices may be employed, this is accomplished in the construction shown by leading the sheet 11 over an upper roller 21 and under the lower roller 22 to cause it to pass beneath and then over the tank 23. This tank contains the hot 5 waterproof adhesive such as asphaltum, which is heated by means not shown, and applied to one face of the paper 11 by the roller 24. The adhesive coated sheet 11 then passes over the supporting bars 25 and 10 beneath the traveling carriers 26 for depositing the attenuated fibres transversely of the sheet. The sheet then passes around the lower roller 27 and upwardly between the nip of the cooperating rollers 28 and 29 15 where it is united with the upper sheet 10. The longitudinal reenforcing fibres are supplied to the nip of the rollers 28 and 29 between the sheet 10 and 11 by the traveling combs 30 and rollers 31. 20
- 25 The adhesive supplied by the tank 23 is relied upon in the construction of Fig. 1 to unite the sheets 10 and 11 and hold the re-enforcing fibres therebetween, and the composite fabric thus formed passes upwardly 30 around the rollers 32 and may be wound into the roll 33.

The mechanism so far described may be similar in construction and operation to that disclosed in the George E. Gibbs application 35 Ser. No. 318,064, filed November 8, 1928.

No particular difficulty is experienced in coating paper with a waterproof adhesive, such as asphaltum, since the adhesive will not pass through the paper to an objectionable degree, but when the adhesive is applied to a textile fabric, such as a cotton sheet, it passes entirely through the sheet unless steps are taken to prevent this.

The present invention, therefore, contemplates the step of chilling the textile fabric 10 sufficiently to cause the heated waterproof adhesive applied thereto to congeal or set quickly before it can penetrate through the fabric to the opposite face thereof.

50 Various constructions may be employed to cool the fabric 10, and this may be done before the hot adhesive is applied to the fabric, as in Fig. 1, or the fabric may be cooled immediately after the hot adhesive is applied thereto, as shown in the modified construction of Fig. 2. The important feature in carrying out the invention is to chill or reduce the temperature of the textile fabric 10 and cause the contacting surface of the 55 adhesive to set or congeal.

The fabric cooling means shown in the drawing comprises a relatively large metal plate 34 supported so that the fabric 10 passing downwardly from the upper roller 17 to 60 the lower roller 35 will slide over its face

and be chilled by its contact therewith. The plate 34 is cooled in the construction shown by providing the pipes 36, 37 for spraying water against a face of the plate, and as the water runs down the plate it may collect in 70 the trough 38 having the discharge pipes 39 and 40. The cooling water may be supplied to the spray pipes 36 and 37 by the pipe 41 having the valve 42.

As a result of the construction just described the textile fabric 10 will be firmly united to the lower sheet 11 by the adhesive applied to the latter and the chilled condition of the textile fabric 10 will cause the adhesive that tends to pass inwardly 75 between the apertures of the fabric to congeal before it strikes through the fabric.

The construction shown in Fig. 2 differs from that of Fig. 1 in that the modified construction of Fig. 2 is shown as provided 80 with means for applying the heated waterproof material to the fabric 10 before it reaches the chilling plate 33. It will be understood, however, that the sheets 10 and 11 are fed rapidly to the nip of the rolls 28 85 and 29 so that the fabric is advanced rapidly from the coating means to the chilling plate and the cooling effect of the latter will cause the adhesive to congeal before it strikes through the textile fabric 10.

90 The means for applying the heated adhesive, such as asphaltum, to the textile fabric 10 of Fig. 2 may be variously contrived but is shown as comprising a tank 43 having the discharge spout 44 adapted to deposit the adhesive upon the fabric in front of the doctor 45.

In the modified construction of Fig. 3 a textile fabric 10 supplied from the roll 14 passes over the roller 46 and downwardly 105 about the outer face of the curved cooling plate 47 to the lower roller 48. The coating of heated waterproofing material is applied to one face of the chilled textile fabric 10 by the tank 49 and doctor 50, whereupon the 110 fabric 10 having one face thereof coated with the waterproof adhesive and the other face free from the coating material may be used for any desired purpose.

Where the textile or woven fabric, which 115 is to be connected by a heated waterproof adhesive, is the open mesh, more advantageous results are secured by applying the heated waterproof adhesive to the textile or woven fabric after the latter has been 120 chilled, as described with respect to Fig. 1 of the drawings. Where, however, the textile or woven fabric is of closer mesh the heated waterproof adhesive may be applied to one face of the woven or textile fabric just 125 prior to the chilling operation, as described with respect to Fig. 2 of the drawings.

The result in either case will be that the textile or woven fabric will present an outer 130 surface which is not discolored by the water-

proof adhesive and such outer surface will therefore not be tacky or sticky even under different weather conditions.

It will be seen from the foregoing that the chilling feature of the present invention constitutes a simple and thoroughly practical method of preventing the heated and liquid coating material from penetrating or passing through the textile fabric.

10 What is claimed is:—

1. The method of producing composite waterproof sheet material having an outer layer of textile fabric and a backing layer of sheet material secured to one face of the textile fabric by a heated waterproof adhesive which consists in chilling the contacting surfaces of the textile fabric and heated waterproof adhesive to set or congeal the contacting surface of the waterproof adhesive and prevent its penetration to the outer surface of the textile fabric, and securing the backing to the textile fabric by the waterproof adhesive.

2. The method of producing composite waterproof sheet material having an outer layer of textile fabric and a backing layer of sheet material secured to one face of the textile fabric by a heated waterproof adhesive, which consists in chilling the contacting surfaces of the textile fabric and heated waterproof adhesive to set or congeal the contacting surface of the waterproof adhesive and prevent its penetration to the outer surfaces of the textile fabric, introducing reinforcing elements and securing them to the textile fabric by the waterproof adhesive, and securing the backing to the textile fabric by the waterproof adhesive.

3. The method of producing composite waterproof sheet material having an outer layer of textile fabric and a backing layer of sheet material secured to one face of the textile fabric by heated asphaltum, which consists in chilling the contacting surfaces of the textile fabric and heated asphaltum to set or congeal the contacting surface of the asphaltum and prevent its penetration to the outer surface of the textile fabric, securing reinforcing unspun fibres between the textile fabric and backing layer of sheet material by the waterproof asphaltum, and securing the backing layer over the reinforcing unspun fibres by asphaltum.

4. The method of producing composite waterproof sheet material having an outer layer of textile fabric which consists in chilling the textile fabric, applying heated waterproof adhesive and a backing layer of sheet material to the chilled textile fabric to set or congeal the contacting surface of the adhesive and prevent its passing through the textile material to the outer surface thereof so that the layer of textile fabric may not be discolored by the adhesive.

5. The method of waterproofing textile

fabrics so that the waterproof coating applied to one surface of the textile fabric shall not penetrate through the textile fabric to the opposite surface thereof which consists in chilling the contacting surfaces of the textile fabric and a heated waterproof coating to cause the contacting surface of the heated coating to set or congeal to an extent sufficient to prevent the coating from penetrating the textile fabric.

In testimony whereof, I have signed my name to this specification.

WILLIAM N. STEVENSON.
